UNITED STATES PATENT OFFICE.

LEW W. LESSLER, OF JOHNSON CITY, NEW YORK, ASSIGNOR, BY MESNE ASSIGNMENTS, TO AGFA ANSCO CORPORATION, OF BINGHAMTON, NEW YORK, A CORPORATION OF NEW YORK.

PLATFORM SUPPORT FOR CAMERAS.

Application filed August 1, 1927. Serial No. 209,979.

My invention relates to means for supporting the platform of a photographic camera of the folding type when the same is lowered to its position for carrying the 5 sliding front of the camera.

The primary object of my invention is to provide a novel type of supporting leg of few parts, easily assembled and which occupies a minimum amount of space on the 10 camera.

A further object is to provide a novel tension device for frictionally maintaining the supporting member in either of its two positions.

15 Other objects and advantages will be apparent as the description proceeds, reference being had to the accompanying drawing wherein like reference numerals indicate like parts.

20 In the drawings:—

Figure 1 is a perspective view of a photographic camera with the platform opened and illustrating the tension device for my improved supporting leg.

25 Figure 2 is a detail plan view of the platform showing the recessed platform for receiving the supporting leg.

Figure 3 is a similar view showing the bearing member mounted on the platform.

30 Figure 4 is a detail perspective view of the bearing.

Figure 5 is a detail perspective view of the supporting leg.

35 Figure 6 is a detail cross section of a part of the camera platform illustrating in side elevation the manner of mounting my improved supporting leg thereon.

The reference numeral 1 indicates generally the body of a conventional type of folding camera provided with the usual spool pins 2, winding key 3, carrying handle 4, sliding front 5, shutter 6, platform 7, and platform supporting brackets 8.

40 Mounted longitudinally of the platform 7 is a strip 9, flanged upwardly and outwardly at its sides to provide tracks or rails 10 upon which the sliding front 5 may move. The strip 9 is preferably cut away as at 11 to lighten its weight. Adjacent the front 45 end of the strip 9, there is struck up an integral, resilient tongue member 12 shown clearly in Figure 1.

50 Directly beneath the free end of the resilient spring tension member 12, the plat-

form 7 is recessed as at 13, and this recess is countersunk as at 14 to receive a bearing member 15, also recessed centrally as at 16 and provided at either end with cup shaped bearing sockets 17 adapted to receive the laterally extending ears or pintles 18 of the 55 supporting leg 19. As shown clearly in Figure 5, one end of the supporting leg 19 is bent upwardly at right angles to the body of the leg and then again forwardly as at 20 in a plane parallel with that of the body 60 of the supporting leg. The laterally extending pintles 18 are formed from the edges of the upwardly extending portion of the leg and as before explained, are adapted to rest 65 in the bearing sockets 17.

70 In assembling the parts just described, the bearing plate 15 is first dropped within the countersunk recess 13 of the platform and the supporting leg 19 is then let down through the openings 16 and 13 until the 75 pintles 18 engage within the bearings 17. The strip 9 is then secured to the platform 7 as by pins or rivets 21 and in such position, the upset end 20 of the supporting leg 80 engages directly against the resilient ten- 85 sion member 12.

The operation of my invention is best illustrated in Figure 6. Normally the supporting leg 19 occupies the position shown in full lines in this figure, that is folded 85 back against the lower surface of the platform 7. In such position, the upset end 20 is parallel with the tension member 12, which exerts sufficient pressure thereon to hold the supporting leg 19 in this position. If now 90 it is desired to use the supporting leg, it is pivoted downwardly to the dotted line position of Figure 6 whereupon the upset end 20 moves back with relation to the spring tension member 12 forcing the same slightly 95 upward to the position shown in dotted lines, and upon passing the "center of gravity," so to speak, the tension exerted by the member 12 will exert itself to hold the supporting leg 19 in its extended position.

100 From the foregoing, it will be clear that I have provided a novel type of supporting leg for the platform of folding cameras which occupies a minimum amount of space on the platform, and which is frictionally held in either of its adjusted positions by the spring tension of the platform rail member.

Obviously, many changes in details of construction and operation may be made without departing from the scope of the invention. I do not limit myself therefore to the exact form shown other than by the appended claim.

I claim:—

In combination with the platform of a camera provided with a countersunk opening, an apertured bearing plate mounted in

said opening, a supporting leg provided at one end with an offset portion and pintles pivotally mounted in said bearing, said leg extending downwardly through said opening and aperture, a fixed rail plate on said platform provided with a resilient tongue struck therefrom overlying said opening and engageable with said offset portion whereby said leg is held in adjusted position. 15

LEW W. LESSLER.
